UNITED STATES PATENT OFFICE.

WALTER S. LANDIS, OF NIAGARA FALLS, NEW YORK, ASSIGNOR TO FRANK S. WASHBURN, OF NASHVILLE, TENNESSEE.

METHOD OF OXIDIZING AMMONIA.

1,193,796.

Specification of Letters Patent. Patented Aug. 8, 1916.

Application filed February 20, 1915, Serial No. 9,595. Renewed June 15, 1916. Serial No. 103,864.

To all whom it may concern:

Be it known that I, WALTER S. LANDIS, a citizen of the United States, residing at Niagara Falls, in the county of Niagara and 5 State of New York, have invented certain new and useful Improvements in Methods of Oxidizing Ammonia; and I do hereby declare the following to be a full, clear, and exact description of the invention, such as 10 will enable others skilled in the art to which it appertains to make and use the same.

This invention relates to a process of catalytically oxidizing ammonia to form oxids of nitrogen, and has for its object to 15 provide a method which will be more efficient in action and less costly to operate on a commercial scale than those heretofore proposed.

With this and other objects in view, the 20 invention consists in the novel steps constituting my process and in the novel combinations of parts found in my apparatus, all as will be more fully hereinafter disclosed and particularly pointed out in the 25 claims.

Referring to the accompanying drawing forming a part of this specification, wherein the figure is a diagrammatic longitudinal sectional view of one form of apparatus 30 suitable for carrying out my process: 1 represents a main for conveying a suitable mixture of ammonia, NH_3 , and air, 2 a connection between said main 1 and the inside of the shell 3 of the apparatus, and 4, a valve 35 in the connection 2. The inside of the shell 3, or the oxidation chamber 15, may be of any suitable size or shape, and is made of any suitable material which will be inert to the contained gases, at temperatures of say 40 700° C. and higher.

In the chamber 15, is located the cooler 16, which is conveniently formed somewhat like the usual type of automobile radiators. That is to say said cooler is conveniently 45 made of very thin sheet material, providing small cells or passages 17, through which the gases may pass, and is also provided with passages not shown for a cooling fluid such as water, or other cooling agent extending at right angles to said passages 17. As it is desirable to keep the temperature as low as possible, one may use any suitable refrigerating fluid in the cooler 16. Said cooling fluid is conveniently led to the passages 50 of the cooler 16, as by the pipe 5, con- 55 nected to the cooler by the pipe 6, provided with the valve 18, all as will be clear to those familiar with the construction of the present day automobile radiators.

7 represents a suitable siphon connected 60 to the cooling fluid passages of the cooler 16, for the purpose of draining the same, and said siphon conveniently discharges into the drain 8. Immediately above the cooler 16, is located the catalytic material 9 preferably 65 composed of finely divided platinum material and through said material 9, I preferably pass a resistor 19, having the lead wires 10, for the purpose of raising the temperature of said material 9 to the desired 70 point to insure the starting of the catalytic reaction, and for the purpose of also maintaining said material at that temperature found necessary to insure the continuance of said reaction. 75

The nitrose gases will pass through the catalyst 9 and collect in the chamber 20, whence they may be drawn off through a connection 21, provided with a valve 22, leading to the main 23. Of course, it will 80 be understood that a plurality of apparatus such as that disclosed may be suitably joined with the mains 1, 5 and 23, and the process carried on simultaneously in each.

In order that the difference between my 85 process and those which have gone before may be the more clearly understood it is said: The oxidation of ammonia to nitric acid has been the subject of experiment and invention for probably seventy years, but 90 up to the present time it has made practically no commercial headway. One reason for this failure to attain a place for this process in the industrial world can be ascribed to the following: (a) The degree 95 of attainable combustion has been very low which entailed serious losses of the valuable reagent; and (b) very little was known in the early days about handling the products of the combustion and converting them 100 into commercially valuable products.

It is well known that ammonia is not combustible in air, like illuminating gas or hydrogen, because its calorific intensity when burned in this manner, is so much below 105 its ignition point that the combustion cannot propagate itself. I have calculated that whereas temperatures of upward of 700° C. are necessary for the propagation of the combustion of ammonia, yet one obtains 110

only about 450° C. by its direct combustion in air, under such proportions of mixture as would insure the ammonia burning to nitrose gases. In oxygen of course it burns 5 without difficulty, according to the reaction:

But the products yielded by this reaction 10 have no commercial value commensurate with the cost of the ammonia. Some seventy years ago it was also noted that ammonia would burn in the presence of a suitable catalyst, according to the equation:

If one desires to write a similar equation representing the combustion in air, we can assume that the air consists approximately 20 of $(\frac{4}{5}\text{N}_2 + \frac{1}{5}\text{O}_2)$ so that our equation would read—

This yields the valuable nitric oxide which 25 can be converted by well known methods into nitrous or nitric acids, or corresponding salts of the same. But as a matter of fact this catalytic combustion with air, or with oxygen, requires more than the theoretical quantity of oxygen to insure complete combustion, and I find it necessary to use from $1\frac{1}{2}$ to $2\frac{1}{2}$ times the theoretical quantity of air, the excess passing through unchanged. Naturally using such an excess of air as above indicated, the flame temperature will be very much lower than that necessary for maintaining combustion. In order, therefore, to assure a continuous combustion of the ammonia it is necessary 35 that some means of supplying heat to the reaction be employed, otherwise the flame will go out, even if started. Many inventors in this field have supplied this additional heat in their commercial forms of apparatus by 40 preheating the mixture of air and ammonia through a regenerative arrangement of apparatus, whereby a portion of the heat in the products of combustion is transferred to the reagents. This portion of heat must be 45 sufficient to make up that deficiency which the reaction does not supply, so as to insure a flame temperature of some 600° C. to 50 700° C. necessary for a continuous propagation of the same. It is likewise well known that ammonia gas is decomposed into 55 nitrogen and hydrogen by heating to comparatively low temperatures; and, therefore, any considerable preheating of the ammonia-air mixture will cause a decomposi- 60 tion of the ammonia before it strikes the catalyst, and so cause a low efficiency of transformation to nitrose gases. It is true that under certain conditions this preheat- 65 ing may not be sufficient to raise the tem- perature of the ammonia to a point where a

serious decomposition will result, but when one considers that the temperatures of the catalysts in use are quite close to the flame temperature, and, therefore, can radiate a large quantity of heat back into the on-coming gas current, we can readily see that the intentional preheating plus the absorbed radiated heat creates temperatures in the ammonia-air mixture which can cause a considerable decomposition of the ammonia. 70 It is further readily seen that under certain conditions this dissociation may take place to only a small extent, thereby setting free hydrogen which has a very low ignition temperature, and that this hydrogen may 75 then be ignited in the air-mixture, creating an excessive local temperature as it burns, and so further increasing this decomposi- 80 tion of ammonia before striking the cata- lyzer. As a matter of fact, I have found 85 that most commercial types of apparatus operating upon this principle decompose from 5 to 15% of the ammonia by a combi- nation of the above causes before the am- monia-air mixture ever strikes the catalyst, 90 and, therefore, they yield a correspondingly low efficiency of transformation of am- monia into nitrose gases.

I have discovered that I can overcome the above objections and obtain very much 95 higher efficiencies in this transformation of ammonia into nitrose gases by the following general combustion principle: Instead of preheating the mixture before it is brought up to the catalyst I intentionally cool it. 100 The more energetic this cooling is the higher the efficiencies, and with some recent types of my apparatus, described in my co- pending application Serial No. 5956 filed Feb. 20, 1915, and entitled Process of and 105 apparatus for oxidizing ammonia, I have succeeded in getting essentially 95% and above, of the ammonia transformed into ni- 110 trose gases. The best results would naturally be obtained by having a very energetic cooler placed approximately one molecular diameter of ammonia from the catalyst surface, but it is self-evident that structural difficulties render impossible the placing of 115 these two things so close together, and I, therefore, must limit myself to placing the cooler as close to the hot catalyst as con- 120 structive details will allow. It is also self- evident that various forms of apparatus for carrying out this process can be used and the one disclosed above is therefore only an example of one form. Accordingly in carrying out my process, I preferably mix the ammonia gas NH_3 , with say an excess of 125 from $1\frac{1}{2}$ to $2\frac{1}{2}$ times the theoretical quantity of air, deliver it to the main 1 which distributes the mixture under pressure through connections 2 to a plurality of combustion chambers 15, and the valves 4, are so regu- 130 lated as to cause said mixture to pass through

the cells 17 of the coolers 16 and through the catalytic masses 9, at such a rate as will produce the best results.

In order to avoid the wasteful dissociation 5 of the ammonia that has been heretofore encountered due to the preheating of the mixture, I cool said air-ammonia mixture as much as is convenient as it passes through the cooler 16 thereby keeping said mixture 10 below say 400° C. or below its dissociation point before it reaches the catalyzer. In other words in order to prevent the ammonia from receiving too much heat from the hot catalyzer just before it reaches the latter, and thereby causing a decomposition 15 to take place, I subject the mixture to the action of the cooler 16, which not only cools the ammonia, but it also prevents the radiant heat of the hot catalyzer from reaching the on coming ammonia. In order that the 20 action of the cooler 16 may be better understood it may be said: Ammonia mixed with air begins to decompose at temperatures upward of 250°-300° C. and this decomposition 25 is extremely rapid at temperatures approaching redness. If now a mixture of air and ammonia is brought up to a catalyzer of such form as to insure an oxidation of the ammonia that strikes it, and the ammonia is 30 not heated above 300° before actually coming into contact with the catalyzer no substantial decomposition will result. The catalyzer is, however, usually at a temperature of about 600°-700° C. and, therefore 35 radiates heat rapidly into the on-coming ammonia. As a result, this on coming ammonia-air mixture usually prior to my invention becomes heated to over 300° C. at a small distance from the catalyzer itself. De- 40 composition has usually, therefore, immediately taken place prior to my invention with a consequent loss in efficiency of transformation of the ammonia. This invention provides a remedy for this trouble by the 45 insertion of a cooler immediately in front of the catalyzer which acts to prevent radiation of the heat from the catalyzer back into the on-coming stream of ammonia gas so that the ammonia may even reach the catalyzer at or below ordinary room temperatures. As the distance between the cooler 50 and the catalyzer is made extremely small in this apparatus, there is practically no opportunity given for the radiant heat from the catalyzer to increase the temperature of 55 the ammonia-air mixture, before said mixture strikes the catalyzer, and consequently, I obtain a very much higher efficiency of transformation of ammonia than has been 60 obtained heretofore. Further, in order to insure that the temperature in the catalyzer shall be maintained sufficiently high to insure an efficient oxidation of the ammonia and thereby prevent the excess of air and 65 other conditions from unduly reducing the

rate of the conversion, I artificially heat the catalyzer 9, as by means of the resistor 19 and circuit 10. It will thus be seen that I preferably provide an excess of air in the mixture, I cool the mixture instead of heating it, and I maintain a temperature above 500° C. and up to say 700° C. or higher in the catalyzer to which the mixture is delivered. I further place the catalyzer as close to the cooler as possible, so as to be able to deliver the mixture at as low a temperature as possible to said catalyzer.

It is of course self-evident that to turn the apparatus upside down and pass the ammonia-air mixture downward instead of upward, or to turn it sidewise and pass the current horizontally would in no wise affect the general principles of the invention. Similarly I do not wish to limit myself to the distance I place the cooler and the catalyzer apart, because that is a matter of structural design only and varies with the different mixtures used, or the degree of combustion one desires to effect. I have found it possible to work as close as 0.04 90 inch without trouble. I have also discovered that I can replace the air in my mixture with oxygen, in which case the combustion will take care of itself after it is once started. In the case of the use of oxygen the temperatures tend to rise so high in the catalyzer that some dissociation of the nitroso gases occurs, and then I find it convenient to place my cooler so close to the catalyzer that I absorb a large amount of the heat of 95 the reaction from this apparatus by direct radiation into my cooler. By this expedient I can keep the temperature down to such a point that no dissociation takes place. I can also use various mixtures of oxygen and 100 air, or enriched air in my apparatus, controlling excessive temperatures by the degree of cooling attained by my cooler. I have further found it convenient to cover the cooler 16 with a wire gauze fabric such as 25, in 110 order to more effectually cool the catalyzer 9.

It is therefore obvious that those skilled in the art may vary the details of my apparatus as well as of my process without departing from the spirit of my invention and therefore I do not wish to be limited to the above disclosure except as may be required by the claims.

What I claim is—

1. The process of oxidizing ammonia which consists in mixing air with said ammonia; passing the mixture through a catalyzing mass the temperature of which is above 500° C.; and preventing radiant heat 125 from entering said mixture and raising its temperature above its point of dissociation just before reaching said catalyzer, substantially as described.

2. The process of oxidizing ammonia 130

which consists in passing a mixture containing ammonia and oxygen through a heated catalyzer; and subjecting said mixture to a cooling means adapted to cut off 5 radiant heat just before it reaches said catalyzer, substantially as described.

3. The process of oxidizing ammonia which consists in providing a mixture containing ammonia and oxygen in suitable 10 proportions; subjecting said mixture to a cooling means adapted to cut off radiant heat just before it reaches the catalyzer; subjecting the cooled mixture to the action of the heated catalyzer; and maintaining the

temperature of said catalyzer above 500° 15 C., substantially as described.

4. The process of oxidizing ammonia which consists in mixing said ammonia with air in excess; cooling said mixture and protecting it from radiant heat; and subjecting 20 the cooled mixture to the action of a heated catalyzer, substantially as described.

In testimony whereof I affix my signature, in presence of two witnesses.

WALTER S. LANDIS.
